UNITED STATES PATENT OFFICE.

CHARLES A. CHANNELL, OF CHICAGO, ILLINOIS, ASSIGNOR TO O-CEDAR CORP'N., OF CHICAGO, ILLINOIS, A CORPORATION OF ILLINOIS.

MOP.

Application filed September 19, 1924. Serial No. 738,561.

This invention relates to a mop and an improved method of making a mop which may be produced cheaply and inexpensively.

It is an object of this invention to provide a mop head adapted to support the mop fabric and provided with a quick attaching and detaching means.

It is also an object of this invention to provide a mop head adapted to support the mop fabric in proper extended relation and having means for conforming with the changes in the size of the mop fabric due to either stretching or shrinkage.

It is a further object of this invention to provide a mop which may be inexpensively made and which is provided with a simple and inexpensive means for attaching and detaching the mop fabric.

It is a further object of this invention to provide a mop head which is stamped out of a single piece of sheet metal to form the top and sides of the head.

It is a further object of this invention to provide a means for making a mop of this class in which the top and sides of the head are formed from a single sheet of metal, the sides being shaped at the ends to form means for frictionally engaging the mop fabric, and in which the means for attaching and detaching the fabric is effective notwithstanding the fact that there may be a relatively wide range of variation in size of the mop fabric.

Other and further important objects of this invention will be apparent from the disclosures in the specification and the accompanying drawings.

The invention (in a preferred form) is illustrated in the drawings and hereinafter more fully described.

On the drawings:

Figure 1 is a side view of the mop.

Figure 2 is a plan view of the mop.

Figure 3 is a section through the line 3—3 of Fig. 2.

Figure 4 is a section through the line 4—4 of Fig. 1.

Figure 5 is also a section through the line 4—4 of Fig. 1.

Figure 6 is a modified detail view.

Figure 7 is a horizontal section of the end of the mop head.

Figure 8 is an end view of the mop head with parts removed.

Like numerals refer to similar parts throughout.

As shown on the drawings:

The mop head comprises a single sheet of metal which is bent down on either side to form a top 3 and sides 1 and 2. Each of the sides 1 and 2 is stamped into the form of a longitudinal groove as shown in Figure 3 to receive a mop fabric 5 which is of the type shown for example in my prior Patent No. 1,254,776. A suitable socket 4 is riveted or otherwise suitably secured to the top 3. The handle is secured in the socket 3 by a pin 12 rigidly secured through the socket. End edges 6 of the sides 1 and 2 are deflected outwardly and act to frictionally engage the mop fabric 5 to maintain the latter firmly and in extended relation in the grooves of the sides 1 and 2.

As shown in Figure 7 the ends of the sides 1 and 2 are cut along the junction with the top 3 to form flexible tongues 13 which are bent inwardly so that they act as braces tending to resist inward pressure on the sides of the mop head and also act to keep a tension on the mop fabric.

Outwardly struck tangs 14 in the sides assist in frictionally binding the fabric. As shown in Figure 4, the attaching and detaching means consists preferably of a bolt 7 which extends through the fabric 5 the sides 1 and 2 and a clamping strip 9 into a position between the adjacent ends of the mop fabric.

The mop fabric is securely held in position by means of a clamping strip 9 apertured to receive the bolt and said strip extends on either side of the bolt into the channel 11 of the fabric 5 and frictionally and securely binds the inner side of said channel against the bottom of the groove of side 2.

As shown in Figure 6 the clamping strip 9 need not extend into the channel 11 of the fabric 5 but may extend along the outside of the hem of said channel to effectually bind the fabric. The strip 9 is very effectively assisted in securing the fabric against accidental removal or disengagement from the mop head by prongs 10 which are forced inwardly against the fabric to binding position by means of a wing nut or other suitable means 8.

Although it is not absolutely necessary, it is frequently desirable to remove the mop fabric of this type from the mop head so that the mop fabric may be washed, cleaned

or renewed. It will be apparent from the structure disclosed that the use of the clamping strip 9 makes it possible to accommodate and use mop fabrics which may vary in length through a relatively wide range. In other words, when the mop is new, the fabric will be stretched tightly to a point where the ends are fairly closely adjacent the projecting end of the bolt 7, and as time goes on, if there is any shrinkage in washing, the mop fabric may still be used effectively owing to the fact that the engaging and clamping prongs 10 are somewhat remote from the bolt 8. On the other hand, in the event the fabric should stretch instead of shrink, the clamping means I have provided is equally of value in that the excess may be threaded over the ends of the clamping strip and compressed sufficiently to permit the fabric to be firmly secured in position as described.

It is obvious that this mop may be cheaply and inexpensively made due to the fact that the head is formed of a single sheet of metal and that since the sides are fashioned as shown forming a clamping means, the additional clamping means is enabled to be less elaborate.

I am aware that many changes may be made, and numerous details of construction may be varied through a wide range without departing from the principles of this invention, and I therefore do not purpose limiting the patent granted hereon, otherwise than necessitated by the appended claims.

I claim as my invention:

1. A mop comprising an elongated sheet metal head having grooved side flanges integral therewith provided with pronged end edges, and a clamping means extending through said grooved flanges between the ends thereof and adapted for securing a mop fabric in operative position in the grooves of said head.

45 2. In a mop, a head provided with inwardly grooved sides, the ends of said sides being spaced and provided with means adapted to penetrate the mop fabric, a mop fabric stretched around the grooved portion 50 of the sides, and a clamping means located between said spaced ends comprising a bolt projecting through said fabric and said grooved sides, said bolt being provided with a clamping element on its free end and 55 adapted to secure the mop fabric in operative position to said head.

3. In a mop, a head provided with inwardly grooved sides, the ends of said sides being spaced and provided with means adapted to penetrate the mop fabric, a mop fabric stretched around the grooved portion of the 60 sides, and a clamping means located between said spaced ends comprising a bolt projecting through said fabric and said grooved

sides and a strip with pronged ends associated with said bolt adapted to secure the mop fabric in its operative position to said head.

4. A mop comprising a sheet metal head, having integral grooved sides provided with pronged end edges, a handle socket secured to said head and clamping means comprising a bolt and a strip secured by said bolt and adapted to cooperate with a side of the head to frictionally clamp the ends of a mop fabric on said head when said fabric is stretched around said head within said grooved sides.

5. A mop comprising a mop head having sides depending therefrom, a mop fabric stretched around said head on said sides, and a clamping means comprising a bolt extending through said fabric and the sides of said head and a strip carried by said bolt, said strip having deflected edges adapted to frictionally engage the ends of said fabric for clamping the fabric to said head.

6. A mop comprising a mop head having a top and a pair of grooved sides, the end portions of said sides terminating in spring tongues projecting inwardly beneath the top for resisting inward pressure and having the end edges deflected outwardly from the periphery of said top, the ends of said head between said sides remaining open, a mop fabric stretched around said head within the grooved sides thereof, clamping means comprising a bolt extending through said fabric and the sides of said head, and a strip carried by said bolt having deflected edges adapted to frictionally engage the ends of said fabric for clamping the fabric to said head.

7. A device of the class described comprising a sheet metal head having sides depending therefrom, said sides being cut a short distance from the ends thereof along the junction with said head to form resilient end portions, a mop fabric stretched around said head on said sides, means for holding said fabric on said head, said end portions acting to keep a tension on said fabric, and a handle for said head.

8. A device of the class described comprising a sheet metal head having sides depending therefrom, said sides being cut a short distance from the ends thereof along the junction with said head to form resilient end portions, the edges of said end portions being deflected outwardly to form prongs, a mop fabric stretched around said head on said sides, means for holding said fabric on said head, said end portions acting to keep a tension on said fabric, and a handle for said head.

In testimony whereof I have hereunto subscribed my name.

CHARLES A. CHANNELL.
